UNITED STATES PATENT OFFICE.

EDWARD F. McCOOL, OF VICTOR, COLORADO, ASSIGNOR TO THE McCOOL MFG. & TRADING CO., OF VICTOR, COLORADO, A CORPORATION OF COLORADO.

DRIVING MECHANISM FOR GRINDING-MILLS.

1,221,760.

Specification of Letters Patent.

Patented Apr. 3, 1917.

Application filed July 26, 1915. Serial No. 42,084.

To all whom it may concern:

Be it known that I, EDWARD F. McCOOL, a citizen of the United States, residing at Victor, county of Teller, and State of Colorado, have invented certain new and useful Improvements in Driving Mechanisms for Grinding-Mills; and I do declare the following to be a full, clear, and exact description of the invention, such as will enable others skilled in the art to which it appertains to make and use the same, reference being had to the accompanying drawings, and to the characters of reference marked thereon, which form a part of this specification.

My invention relates to improvements in grinding mills of the class covered by my Letters Patent of the United States Nos. 1,137,224; 1,138,966; 1,139,790 and 1,144,305, and dated April 27; May 11; May 18 and June 22, 1915, respectively.

My present improvement relates to means for transmitting motion to a shaft eccentrically mounted within a sleeve or hollow shaft, the eccentrically mounted shaft being connected in operative relation to rotate a grinding member which is arranged in co-operative relation with another grinding member, the latter in the specific construction disclosed being stationary.

Heretofore or in the constructions disclosed in the aforesaid patents the power is applied in the first instance to the sleeve or hollow shaft, motion being transmitted to the eccentrically mounted shaft through the medium of a suitable gearing connection.

I have found that it is possible to dispense with this gearing connection, by applying the power in the first instance to the eccentrically mounted shaft, since it is possible to impart a certain degree of rotary movement to the sleeve, and in this way impart some degree of orbital travel to the eccentrically mounted shaft, the object being to give enough orbital travel to the eccentrically mounted shaft and the disk connected therewith, to cause the co-operating members to wear evenly and avoid the grooving, which grooving it is the object of the eccentric shaft construction to prevent. I have found by actual demonstration that a certain degree of movement may be imparted to the sleeve or hollow shaft in this manner and I

am thus confident that the present invention has at least a sufficient degree of utility to 55 justify the making of this application.

I am also disclosing in this application a system of lubrication for grinding mills of this construction, whereby the oil is taken from a reservoir in the framework, carried 60 upwardly and fed to a passage formed in the center of the eccentrically mounted shaft, from which it is carried by virtue of radially disposed perforations in the shaft by the action of centrifugal force, to all the various 65 parts to be lubricated.

Having briefly outlined my improved construction, I will proceed to describe the same in detail, reference being made to the accompanying drawing in which is illustrated an 70 embodiment thereof. In this drawing,

Figure 1 is a central vertical longitudinal section of a grinding mill equipped with my improvements.

Fig. 2 is a similar view of the rear extremity of the mill shown on a larger scale.

Fig. 3 is a section taken on the line 3—3, Fig. 2, looking toward the left.

Fig. 4 is a section taken on the line 4—4, Fig. 1, looking toward the left.

The same reference characters indicate the same parts in all the views.

Let the numeral 5 designate a suitable framework which is formed hollow to receive a quantity of oil or liquid lubricant 6. 85 Within this framework is journaled a sleeve or hollow shaft 7 in which is eccentrically mounted a shaft 8, to the forward or left hand extremity of which is connected a disk or grinding member 9 the connection being 90 such as to cause the said member to rotate with the shaft. The rear or opposite extremity of this shaft is equipped with a relatively hard thrust block or end bearing member 10 whose rear extremity is engaged 95 by a disk 12 whose rear side is in contact with a roller bearing member 13, in the rear of which is located a bearing disk 14 set into a block 15 which is connected with the casing as shown at 16 to prevent rotation. 100 This block is engaged by a screw 17, by the adjustment of which, the shaft 8 is adjusted in an endwise direction to regulate the pressure of the grinding member 9 upon its co-operating stationary grinding member 18. 105

Outside of the sleeve or hollow shaft 7

and surrounding the same is a bearing sleeve 19 to the forward extremity of which is secured an operating pulley 20, the pulley being connected with the sleeve by means of a key 21. The rear extremity of this bearing sleeve is provided with projections 22 which enter openings 23 formed in the web of a wheel 24 which is made fast to the rear extremity of the eccentrically mounted shaft 8 by means of a key 25. By virtue of this construction the operating pulley 20 is connected to rotate the shaft 8 on its own axis within the eccentrically arranged bearing of the hollow shaft 7. This hollow shaft 7 engages at its rear extremity the hub of the wheel 24 carried by the shaft 8. Furthermore the forward or left hand extremity of the hollow shaft 7 engages as shown at 26 the rear extremity of the hub 27 of a fan blower 28 which is connected by means of a key 29 with the forward extremity of the shaft 8 just in the rear of the grinding member 9, the grinding member and the hub 27 being spaced by a spiral spring 30, whereby the hub of the fan blower is forced against the forward extremity of the hollow shaft 7. From this it will be understood that the hollow shaft 7 engages at its opposite ends, parts 24 and 27 which are connected to rotate with the shaft 8 which is positively rotated by virtue of its connection with the pulley 20. By virtue of this construction and arrangement, it is safe to conclude that as the shaft 8 is rotated some rotary movement will be imparted to the hollow shaft 7, and to the extent that the last named shaft moves rotatably, an orbital travel will be imparted to the eccentrically mounted shaft 8, in addition to the rotation of the shaft 8 on its own axis. By virtue of this orbital travel of the shaft 8, a gyratory travel will be imparted to the grinding member 9, whereby the two grinding members will be caused to wear evenly during their co-operative action, thus preventing grooving.

The hub 27 of the fan blower 28, is connected with the hollow shaft 7 to prevent endwise displacement by means of a segment shaped key 31 which is dropped into a groove of corresponding shape formed in the connected parts, the key being of sufficient depth to extend into the groove of both members. The construction and arrangement of the fan blower connected with the shafts 8 and 7 as just explained, is consistent with the rotary movement of the shafts 7 and 8 in co-operative relation as heretofore described.

The upper part of the rear extremity of the framework contains a receptacle 32 which is formed in part by an interior wall 33 arranged outside of the wheel 24, and adapted to permit the rotation of said wheel. During the rotation of the shaft 8 and the wheel 24, the latter dips into the liquid lu-

bricant 6 in the lower part of the framework and carries this lubricant upwardly and discharges it beyond the wall 33 into the receptacle 32 from which it is fed through an orifice 34 into an opening 35 in the block 15, whence it passes into an opening 36 in the said block, which opening is in register with an opening 37 in the disk 14, the opening 37 being in communication with openings 38 and 39 in the parts 10 and 12, the last named openings communicating with the rear extremity of the longitudinal passage 40 in the shaft 8. In this way the oil or other liquid lubricant enters the passage 40 of the last named shaft and is distributed by the action of centrifugal force and by way of perforations 41 in the shaft 8, 42 in the shaft 7, and through co-operating ports and passages, to the various surfaces of the moving parts requiring lubrication. The liquid lubricant 6 is located in the front portion of the casing as well as in the rear portion, the lubricant 6 in the front part of the casing being carried upwardly by a wheel or circular member 43 mounted on the hollow shaft 7, and deposited in a receptacle 44, whence it travels through an opening 45 to a passage 46 communicating with the receptacle 32. In this way the oil is transferred from the front portion of the casing, to the receptacle 32 and thence to the center passage of the shaft 8.

The two receptacles 32 and 44 are closed respectively by caps 47 and 48 which are removable to permit access thereto when required. These caps are preferably provided with lubricant collecting plates or springs 48 which facilitate the transfer of the oil from the lower part of the casing to the receptacles 32 and 44.

The structure is further provided with rings 49 which are hung loosely on the hollow shaft 7 and dip into the lubricant 6 in the reservoir formed in the lower part of the casing as heretofore described.

These rings during the rotation of the hollow shaft, may be relied on for distributing the lubricating material to some extent.

From the foregoing description the use and operation of my improved construction will be readily understood and need not be explained further in detail.

Attention is called to the fact that the upper segments of the rings 49 are located in recesses 50 formed in the bearing sleeve 19 in which the hollow shaft 7 is journaled. By virtue of this construction, these lubricating rings rest directly upon the hollow shaft and they are held in place against displacement lengthwise of the hollow shaft by virtue of the formation of the recesses 50 which form openings through which the oil carried upwardly by the rings is directly applied to the hollow shaft and from it to co-operating parts requiring lubrication.

Having thus described my invention, what I claim is,—

1. In a grinding mill, a hollow shaft, a second shaft eccentrically mounted therein, means for positively rotating the second shaft on its own axis and to permit orbital travel with the hollow shaft, and means fixedly carried on said second shaft frictionally engaging said hollow shaft for imparting rotary movement to the latter. 15
- 5 2. In a grinding mill, a hollow shaft, a second shaft eccentrically mounted therein, and means for applying power to the second shaft to rotate the latter on its own axis and to permit orbital travel with the hollow shaft, the second shaft having parts connected to rotate therewith and in frictional contact with the opposite extremities of the hollow shaft to impart rotary movement to the latter. 20
- 10 3. In a grinding mill, a hollow shaft, a second shaft eccentrically mounted therein, means for positively rotating the second shaft on its own axis and to permit orbital travel with the hollow shaft, and means fixedly carried on said second shaft frictionally engaging said hollow shaft for imparting rotary movement to the latter. 25

In testimony whereof I affix my signature in presence of two witnesses.

EDWARD F. McCOOL.
